UNITED STATES PATENT OFFICE.

ALBERT L. REA, OF SHAWNEE, OHIO.

AUTOMATIC STUFFING BOX.

Application filed October 10, 1921. Serial No. 506,935.

To all whom it may concern:

Be it known that I, ALBERT L. REA, a citizen of the United States, residing at Shawnee, in the county of Perry and State 5 of Ohio, have invented certain new and useful Improvements in Automatic Stuffing Boxes, of which the following is a specification.

This invention relates to stuffing boxes 10 for use in connection with moving rods such as piston and pump rods and more particularly to polished rods used in oil wells.

The object of the invention is to provide 15 a box of this character which uses very little packing and requires very little attention after it has once been packed.

Another object is to provide a stuffing box of this character constructed so that 20 the packing will be released after the well has been pumped off and allowed to stand for a time thus leaving the packing practically loose and avoiding heating of the rod and burning out of the packing as well 25 as the consequent leakage and waste of the oil.

With these and other objects in view, the invention consists in certain novel features of construction as hereinafter shown, de- 30 scribed and claimed.

In the accompanying drawing:—

Figure 1 represents a longitudinal section through the casing of the stuffing box with the packing and cooperating parts in side 35 elevation, one of the followers being broken out and in section.

Fig. 2 is a plan view of the device the rod being shown in section, and

Fig. 3 is a transverse section taken on the 40 line 3—3 of Fig. 1.

Oil wells have two valves at the bottom of the tubing known as the standing valve and the working valve and after these valves have become worn they begin to leak and 45 the fluid drops down in the tubing leaving the tubing partly empty so that when the pump is first started there is no oil around the packing and the working up and down therethrough of the polished rod causes the device to become heated by friction and burns out the packing permitting the oil to run out on the ground and be wasted. It is to overcome this objection 50 that this device was designed.

In the embodiment illustrated the device

constituting this invention comprises a casing 1 having a laterally extending outlet branch 2 near its lower end which is threaded internally for connection with the lead line (not shown) and to the upper end of 60 which is applied a cap 3 having threaded connection with the casing 1 and provided with a central opening for the passage of the polished rod 5, said opening being surrounded by a flange 4.

A seat or shoulder 6 is formed within the casing 1 in a plane above the lower or bottom wall of the opening 2 and is designed to form a rest or stop for the lower fol- 65 lower 7 said follower being on the rod 5 as 70 is shown clearly in Fig. 1.

The packing is mounted above the follower on the rod 5 and as shown is in the form of a plurality of soft rubber rings 8 and 9 three of each being shown arranged in 75 alternation the larger rings 8 being of soft rubber while the smaller rings 9 are of any suitable material.

Above the packing rings 8 and 9 is the top follower 10 and between the upper face 80 of this follower 10 and the inner face of the cap 3 is a coiled spring 11.

In the use of this improved stuffing box the casing 1 is first screwed onto the top 85 of the well tubing (not shown), and the lead line (not shown) is connected with the outlet opening 2 of said casing. The lower follower 7 is then placed within the casing 1 almost covering the outlet opening in the side thereof and resting on the seat 6. The packing rings 8 and 9 are then placed on the follower 7 and the top follower 10 placed over said packing with the coiled spring 11 arranged above the top follower 10 be- 90 tween it and the cap 3. The end of the spring 11 when so placed extends above the top of the casing 1 about an inch more or less. The cap 3 is then tightened down which compresses the spring 11 sufficiently 95 to compress the packing rings 8 and 9 to prevent leaking until the well begins to pump. When this occurs the fluid strikes the lower follower 7 and raises it against the tension of spring 11 thereby tightening 100 the packing and permitting the fluid to pass out through the opening 2. It is of course understood that the follower is raised suffi- 105 ciently to allow whatever fluid the rod produces to pass out through the outlet opening. After the well is pumped off and is allowed 110

to stand for awhile the valve leaks permitting the fluid to pass back into the tubing. The packing is thus released and the follower 7 drops down onto the seat 6.

5 When the pump is again operated the packing is practically loose and hence the rod 5 does not become heated and the packing remains in this condition until the fluid comes in contact with the lower follower 7 10 thereby causing the packing to tighten by contact with the fluid requiring no tools to effect this operation.

After the stuffing box is once packed and placed in operative position it will give 15 perfect satisfaction without requiring any attention and lasts from two weeks to two months according to the smoothness of the rod 5.

From the above description it will be obvious 20 that a bushing constructed as herein shown and described will operate automatically to compress and release the packing according to whether the well is pumping or left unused.

25 The preferred embodiment of the invention is disclosed in the drawings and set forth in the specification, but it will be understood that any modifications within the scope of the claimed invention may be 30 made in the construction without departing from the principle of the invention or sacrificing any of its advantages.

I claim:—

1. A stuffing box for pump rods and the

like, comprising a pump rod, a casing 35 through which the pump rod extends and having an outlet opening at one side, a follower in said casing mounted on the rod to partially close said opening, a compressible packing surrounding the pump rod and arranged on said follower, another follower 40 on the rod arranged over said packing and resting thereon, an adjustable cap enclosing the upper end of said casing, and a coiled spring arranged between said cap and last 45 mentioned follower, said spring tensioned to normally hold the first mentioned follower in position to partially close the opening.

2. A stuffing box for pump rods and the 50 like, comprising a pump rod, a casing for connection with a well tubing and having an outlet opening on one side near one end, said casing being provided with a seat arranged above the lower wall of said opening, 55 a follower in said casing normally resting on said seat and partially closing said opening, a plurality of packing rings mounted in said casing on said follower and surrounding the pump rod, another follower 60 on the rod mounted on said packing rings, a cap having threaded connection with the upper end of said casing and apertured for the passage of the pump rod, and a coiled spring mounted in said casing between said cap and said last mentioned follower.

65 In testimony whereof, I affix my signature hereto.

ALBERT L. REA.
